CLAIM

The ornamental design for the head mounted device, as shown and described.

DESCRIPTION

FIG. 1 illustrates a right side view of a head mounted device; FIG. 2 illustrates a left side view of the head mounted device; FIG. 3 illustrates a top plan view of the head mounted device; FIG. 4 illustrates a bottom view of the head mounted device; FIG. 5 illustrates a rear perspective view of the head mounted device;

FIG. 6 illustrates a rear view of the head mounted device; FIG. 7 illustrates a front perspective view of a first variant of the head mounted device;

FIG. 8 illustrates a front view of the first variant of the head mounted device;

FIG. 9 illustrates a front perspective view of a second variant of the head mounted device;

FIG. 10 illustrates a front view of the second variant of the head mounted device; and,

FIG. 11 illustrates a sectional view of the head mounted device taken along the line 11-11 in FIG. 3.
